Maurice Lachman, INVENTOR.

BY

15 Townsend Wecker, ATTORNEYS.

UNITED STATES PATENT OFFICE.

MAURICE LACHMAN, OF NEW YORK, N. Y., ASSIGNOR TO STRUCTURAL PRESSED STEEL WHEEL COMPANY, INC., OF NEW YORK, N. Y., A CORPORATION OF NEW YORK.

METAL WHEEL.

1,215,553.

Specification of Letters Patent.

Patented Feb. 13, 1917.

Original application filed June 12, 1916, Serial No. 103,145. Divided and this application filed July 12, 1916. Serial No. 108,875.

To all whom it may concern:

Be it known that I, MAURICE LACHMAN, a citizen of the United States, and a resident of New York, in the county of New York and State of New York, have invented certain new and useful Improvements in Metal Wheels, of which the following is a specification.

My invention relates to the construction of metal wheels and more particularly to those embodying sheet metal disks having openings to form spokes integral with a continuous rim and center.

The object of my invention is to provide a construction of great strength and low cost of manufacture.

To these ends my invention consists essentially in folding or doubling the edge of the metal around at each opening to form a tubular reinforcement preferably integral with the material of the disk.

By this construction the substantially flat structure of the disk which in its plate form is adapted to bear a load or weight supported by the axle and is little suited to resist lateral stresses or twisting strains is effectually reinforced and a wheel of small weight and pleasing appearance may be successfully produced. Furthermore, no objectionable raw projecting edge of sheet metal exists around the openings in the disk.

In the accompanying drawings Figure 1 is a side elevation of a wheel embodying my invention.

Fig. 2 is a side elevation of the blank disk from which the structure is produced.

Fig. 3 is an edge view of the same.

Fig. 4 is an enlarged transverse section taken on the line 4, 4 Fig. 1.

Fig. 5 is an enlarged section through the material of the disk at the edge of the opening.

The blank sheet metal disk shown in edge view in Fig. 3 is formed with openings as shown at 1 in Fig. 2 to constitute spoke portions 4 integral with the continuous rim 2 and with the hub or center portion 3. Holes 8 may be provided in the center portion 3 for attachment of the disk to standard hubs, as usual in the art, and the rim 2 may be furnished with any style of metal or rubber tire carrying element secured to or formed there-

with in any desired manner. The opening 5 in the center is for the axle or other supporting spindle.

As a plain disk and not reinforced a wheel constructed from a sheet metal disk as described might have sufficient strength to support light loads but would have little resistance to lateral strain or twisting. To reinforce the disk to take lateral strains while preserving its general characteristics as a disk, I propose to fold or turn the edge of the metal around the opening 6 upon itself as indicated at 15, such folding or doubling being preferably done in a manner to form, as shown, a tubular reinforcement at the edges of the flat metal spokes and rim around the openings 1. Also, if desired, the outer edge of the disk or rim 2 may be similarly formed and likewise the edges of the opening 5 in the hub or center portion 3.

When the segmental openings indicated are rounded as shown at the center portion 3, said reinforcement is preferably continued around the edge of the opening to include such rounded portion. By this construction it will be seen that a section through one of the spokes or across the rim part will present substantially an I beam section which, as is well known, is a form of metal section well adapted to resist strain in directions at right angles to one another.

It will also be seen that no raw projecting metal edge is exposed, so that the wheel will present a smooth appearance and no objectionable projecting edges.

It is obvious that a single disk, as shown might be used as a wheel or that a number of the same might be employed together to make a wheel.

My present application is a division of a prior application filed by me, Serial No. 103,145, filed June 12th 1916.

What I claim as my invention is:

1. In a sheet metal wheel, a metal disk having openings to form spokes integral with the continuous rim and center and a continuous tubular reinforcement around each opening formed of metal integral with the metal of the flat portion of the disk.

2. In a sheet metal wheel, a sheet metal disk having openings to form spokes integral with the continuous rim and center, the

edges of the flat metal spokes and rim around said openings being bent into the form of a tube.

3. In a sheet metal wheel, a sheet metal disk having openings to form spokes integral with the continuous rim and center and a continuous tubular reinforcement around each said opening in the flat metal.

4. In a sheet metal wheel, a plate embracing a hub or center portion, spokes or arms radiating therefrom and a continuous rim all integral and having on the edge of the metal plate around each opening bounded by spokes and rim a tubular reinforcement integral with the metal of the plate.

5. In a sheet metal wheel, a sheet metal disk having openings to form spoke, center and rim portions all integral, the edges of the flat metal of said rim and spokes around the openings being bent into the form of a tube and a tubular reinforcement around the periphery of the rim as and for the purpose described.

Signed at New York, in the county of New York and State of New York, this 11th 25 day of July A. D. 1916.

MAURICE LACHMAN.
